SPACE CHARGE WAVE AMPLIFIERS

Lester M. Field, Palo Alto, Calif., assignor to The Board of Trustees of the Leland Stanford Junior University, Stanford University, Calif., a legal entity of California having corporate powers

Application December 29, 1951, Serial No. 264,031

7 Claims. (Cl. 315—3.6)

This invention relates to improvements in the art of amplifying high frequency electromagnetic wave energy, and particularly to methods and apparatus for effecting amplification by means of space charge waves on a stream of electrons.

One of the principal objects of the invention is to provide electron discharge tubes capable of a high degree of amplification throughout extremely wide bands of microwave frequency spectrum.

Another object is to provide high frequency amplifier devices of rugged and simple construction, wherein modulation of an extended electron beam is built up by a succession of abrupt changes in D.-C. velocity along the beam.

The invention will be described with reference to the accompanying drawings, wherein:

Fig. 1 is a schematic diagram of an amplifier embodying the invention in a presently preferred form,

Fig. 2 is a graph showing the D.-C. potential distribution and D.-C. velocity along the path of the electron stream in the tube of Fig. 1,

Fig. 3 is a graph showing the amplitude of the A.-C. current and A.-C. velocity in the electron stream as a function of position along the path, corresponding to the potential distribution of Fig. 2, and

Fig. 4 is a schematic diagram of a modified embodiment of the invention, incorporating two cascaded stages.

The present application is a continuation-in-part of U. S. patent application Serial No. 253,344, entitled Space Charge Wave Amplifiers and filed October 26, 1951, in the names of Ping King Tien and Lester M. Field.

According to this invention, the signal to be amplified is impressed on an electron beam to set up plasma oscillations or space charge waves comprising correlated variations of A.-C. current density and A.-C. velocity along the beam. The beam is then decelerated abruptly, at a point where the A.-C. velocity is at a maximum, to a relatively low D.-C. or average velocity which may be a small fraction of its initial D.-C. velocity. Then, at a subsequent point along the path of the beam when the A.-C. velocity due to the impressed signal is zero, the beam is abruptly accelerated to a relatively high D.-C. velocity, for example that which it had where the signal was applied. This series of operations on the beam produces a new set of space charge waves like those caused by the input signal, but of substantially greater amplitude. The process may be repeated a number of times on the same beam, if desired, by decelerating the beam and accelerating it again at successive respective points of maximum and zero A.-C. velocity. Each repetition produces a considerable increase in the modulation of the beam, up to the point where the A.-C. velocity and A.-C. current density become large enough to cause saturation effects. The amplified signal may be taken off the beam by suitable means responsive to A.-C. current density and/or A.-C. velocity, for example a conductive helix.

The amplifier shown in Fig. 1 includes an electron gun 1 arranged to project a beam of electrons along a longi-

2

tudinal axis to a collector electrode 3. The gun 1 may be of known design, comprising a cathode 5, focussing electrode 7, and an anode or accelerator electrode 9. A short conductive helix 11 surrounds the path of the electron beam in the region of the gun 1. A similar helix 27 surrounds the path of the beam near the collector 3. The initial turn of the helix 11 may be stretched out as shown at 15 to provide a small probe or antenna for coupling to an input wave guide 33. The helix 27 is similarly coupled at 29 to an output guide 35.

The helices 11 and 27 are similar to those used in travelling wave tubes, but they need not be made long enough to produce any substantial amplification. Their purpose is to modulate the beam with an input signal applied to the guide 33, and to take the amplified signal off the beam for transmission by the output guide 35 to utilization means. While it is preferred at present to use helices as shown, other known means may be employed for modulating the beam and extracting oscillatory energy from the beam, for example electrodes such as grids. In a typical tube which has been constructed, the helices 11 and 13 were wound of 0.01 inch diameter tungsten wire with a pitch of 26 turns per inch, and an inside diameter of 0.1 inch.

15 20 25 A plurality of apertured conductive disc electrodes 17, 18, 22, 24 and 26 surround the path of the electron beam at spaced points between the helices 11 and 27. The electrodes 17 and 18 may be connected together by a cylindrical conductive tube 13 as shown, for supporting them in alignment within the vacuum envelope 39. The first electrode 17 is disposed adjacent the inner end of the input helix 11, and may be connected thereto. The second electrode 18 is spaced from the first by a distance indicated as D on the drawing. This distance depends 30 35 upon the conditions under which the tube is designed to operate, and may, in a typical case, be about one and three quarters inches.

The third electrode 22 may be located as near the electrode 18 as is feasible without the risk of voltage breakdown and arcing between the two elements. The fourth electrode 24 is spaced from the electrode 22 by a distance D', determined by the operating conditions, as will be explained. The separation between the electrodes 22 and 24 may in some cases be the same as that between 40 45 electrodes 17 and 18. The electrodes 22 and 24 are connected together by a tubular member 19, like the tube 13. The fourth and fifth electrodes 24 and 26 are separated by a relatively small space, like that between the electrodes 18 and 22. The electrode 26 may be connected 50 internally to the end of the output helix 27.

A D.-C. source 37 is connected as shown to maintain the accelerator 9, and helices 11 and 27, the electrodes 17, 18 and 26, and the collector 3 at a high positive potential with respect to the cathode 5. In a tube having the dimensions and proportions given above, this potential may be about 1900 volts. The electrodes 22 and 24 are connected to a point 38 of relatively low voltage, say about 75 volts, on the source 37. Preferably a voltage divider 40 is included to provide for convenient adjustment of 55 60 65 this voltage. The cathode 5 may be heated in usual manner by current from an external source, not shown.

In the operation of the device, the electron gun 1 projects a beam of electrons along the axis of the tube, through the helix 11, electrodes 17, 18, 22, 24 and 26, and the helix 27, to the collector 3. The initial D.-C. velocity of the beam as it leaves the gun and passes through the helix 11 is relatively high, owing to the high potential of the accelerator 9. This velocity should be substantially equal to the velocity of wave propagation 70 along the helix 11, e. g. about one tenth the velocity of light. The term "D.-C. velocity" as used herein means the average velocity of the electrons in the part of the

stream under consideration, and is designated by the letter u . Cyclical variations in the velocity of electrons passing through a given plane across the stream are referred to as the "A.-C. velocity."

In an ideal unmodulated electron stream, all of the electrons move at the D.-C. velocity u , and the electron density or charge density remains constant at a D.-C. value ρ . Now consider the stream to be sinusoidally modulated by cyclically accelerating and decelerating it at some transverse plane. The velocity at this plane is then $u + v \sin 2\pi f_m t$, where v is the magnitude of the A.-C. velocity and f_m is the modulation frequency. Assume that v is much less than u , as is the case in the practice of the present invention. As the stream flows on, the electrons which are accelerated will get ahead of their normal or equilibrium positions, and those which are decelerated will get behind their equilibrium positions, so that the stream becomes formed into relatively concentrated bunches of electrons which are separated by rarified regions.

Owing to the mutual repulsion between electrons, the bunches will spread out and coalesce, and the stream will be of substantially uniform density again at some point along its path. Here the electrons are in their original equilibrium positions with respect to each other, the axial repulsion forces exerted on each electron by those ahead of it being balanced by those behind it. However, the electrons at this point are moving with respect to their equilibrium positions, and momentum carries them past those positions in the opposite directions from those in which they were originally displaced. Thus the stream is bunched again, at some subsequent point, and the cycle repeats itself.

This phenomenon is called plasma oscillation, or space charge oscillation. The frequency f_p of oscillation of the electrons about their equilibrium positions depends upon the restoring force exerted on an electron per unit of its longitudinal displacement from equilibrium, and is substantially proportional to the square root of the D.-C. charge density ρ . The distance through which the stream moves at the D.-C. velocity u during one cycle of such oscillation is

$$\frac{u}{f_p}$$

and is called the space charge wavelength, λ_p .

Where the bunching is complete, the electrons are reversing their directions of motion with respect to the stream as a whole, i. e. those which have been travelling more slowly, having nearly been overtaken by the bunch, are being repelled forward and accelerated, and those faster ones which have nearly overtaken the bunch are repelled in the rearward direction from the bunch. Thus, the A.-C. velocity v at these points is zero, notwithstanding the fact that the stream is modulated. This statement is based on the assumption that the original velocity modulation is small compared to the D.-C. velocity u , so that the electrons do not have enough momentum to overcome the repulsion forces and pass through the bunch. The distance along the stream between consecutive points of zero A.-C. velocity is

$$\frac{\lambda_p}{2}$$

one half the space charge wavelength, and these points are fixed with respect to the point where the modulation is applied. Midway between these points, the A.-C. velocity is maximum, alternately in the direction of the stream and in the opposite direction. Thus the magnitude of the A.-C. velocity varies periodically as a function of distance along the beam from any fixed reference point, the length of the complete period being one space charge wavelength. This variation of the magnitude of the A.-C. velocity with position along the path of the stream may be regarded as a standing wave, fixed in space.

Where the A.-C. velocity is at a maximum, either positive or negative, the electrons are in their equilibrium positions and therefore the current density is uniform at the D.-C. value q^0 . At all other points in the beam the current density will vary at the modulation frequency f_m , above and below q^0 by some amount q . This is the A.-C. current density, and it also varies in magnitude as a function of distance along the beam, being zero where the A.-C. velocity is maximum, and maximum where the A.-C. velocity is zero. Thus we have a standing wave of A.-C. current density magnitude, correlated with the A.-C. velocity magnitude wave, and 90 degrees out of space phase with it. The amplitudes of these waves are definitely related to each other because all of the modulation energy is transferred cyclically from one form to the other.

The modulation may be applied as pure velocity variation, as described above, or as density variation, since either one will become converted to the other and back again, producing the same sort of space charge waves. Furthermore, a mixture of the two kinds of modulation will do the same thing, the effect being to start the waves at a point where neither is of zero amplitude.

In the device of Fig. 1, an input signal applied through the wave guide 33 to the helix 11 will modulate the electron stream, in the same manner as in a travelling wave tube. When the beam leaves the helix, it carries correlated waves of A.-C. velocity and A.-C. current density due to space charge oscillation, the space charge frequency f_p and wavelength λ_p being determined by the D.-C. charge density ρ and D.-C. velocity u .

Referring to Fig. 3, it is assumed for generality that the space charge waves at the point a at the electrode 17 on the end of the helix 11 have a current density amplitude q_a and velocity amplitude v_a , neither being zero. At some subsequent point b along the stream, the A.-C. current density will be zero and the A.-C. velocity will be at a maximum value v_b . The distance D between electrodes 17 and 18 (Fig. 1) is determined in accordance with the initial D.-C. charge density ρ and velocity u , and the relationship between A.-C. current density and velocity at the point a , so as to make the velocity maximum v_b occur approximately at the plane of the electrode 18. This distance may be found experimentally, or computed analytically, taking into account that the plasma frequency and space charge wavelength differ from their ideal values because the stream is of finite cross section. As a practical matter the distance D is not very critical, and may differ widely from the theoretical optimum without serious effect upon the operation of the tube.

In crossing the gap 21 between the electrodes 18 and 22, the beam is decelerated abruptly from the relatively high D.-C. velocity u , corresponding to say 1900 volts, to a relatively low D.-C. velocity u' corresponding to the potential of the electrode 22, for example 65 volts. The total D.-C. beam current I is the same on both sides of the gap 21, and is the product of the D.-C. velocity and D.-C. charge density at each point. Therefore

$$\rho' = \frac{u}{u'} \rho$$

where ρ' is the charge density on the low potential side of the gap 21. As mentioned above, the plasma frequency is proportional to the square root of the D.-C. charge density. Accordingly, the plasma frequency in the space between the electrodes 22 and 24 is

$$f'_p = f_p \sqrt{\frac{\rho'}{\rho}} = f_p \sqrt{\frac{u}{u'}}$$

The space charge wavelength, being equal to the D.-C. velocity divided by the plasma frequency, is proportional to the three halves power of the velocity:

$$\frac{\lambda'_p}{\lambda_p} = \left(\frac{u'}{u} \right)^{3/2}$$

Thus the original set of space charge waves is converted

at the gap 21 to a new set, similar to the first but of substantially shorter wavelength, λ'_p .

Consider an electron having a D.-C. velocity u_1 . The kinetic energy is $\frac{1}{2}mu_1^2$, where m is the electron mass. Let the electron be decelerated by passing through a potential drop of E volts. The kinetic energy is then less by the amount Ee , where e is the electron charge, and

$$\frac{1}{2}mu_1^2 - \frac{1}{2}mu_2^2 = Ee$$

u_2 being the D.-C. velocity after deceleration. Now suppose that besides the D.-C. velocity u_1 , the electron had a relatively small A.-C. velocity of instantaneous value v_1 . Then the kinetic energy before deceleration is

$$\frac{1}{2}m(u_1+v_1)^2$$

and after acceleration is $\frac{1}{2}m(u_2+v_2)^2$. Thus

$$\frac{1}{2}mu_1^2 + mu_1v_1 - \frac{1}{2}mu_2^2 + mu_2v_2 + \frac{1}{2}mv_2^2 = Ee, = \frac{1}{2}mu_1^2 - \frac{1}{2}mu_2^2$$

(from the above equation)

Collecting the terms and factoring m , this becomes

$$u_1v_1 + \frac{1}{2}v_1^2 = u_2v_2 + \frac{1}{2}v_2^2$$

Since v_1 and v_2 are small compared to u_1 and u_2 , their squares can be neglected, and

$$u_1v_1 = u_2v_2$$

The instantaneous A.-C. velocity after deceleration is therefore

$$v_2 = \frac{u_1}{u_2} v_1$$

It is apparent that the new A.-C. velocity is greater than the initial A.-C. velocity, in the same ratio that the original D.-C. velocity is greater than the new D.-C. velocity.

Returning to Fig. 3, the A.-C. velocity v'_b on the exit side of the gap 21 is

$$\frac{u}{u'}$$

times the velocity v_b on the entrance side. The current density is substantially the same on both sides of the gap, because the gap is short compared to the space charge wavelength and the electrons do not have time to change their relative positions appreciably during the transit. Thus the new set of space charge waves originating at the gap 21 starts a velocity maximum and current zero, and the A.-C. velocity amplitude is

$$\frac{u}{u'}$$

times that of the original waves. The A.-C. current amplitude is correspondingly increased, reaching a maximum value q_e at a point c , one quarter space charge wavelength further along the beam.

The distance D' between the electrodes 22 and 24 is made equal to one quarter the new space charge wavelength λ'_p , so that the gap 25 is at the point c , or it may be any odd integral multiple of

$$\frac{\lambda'_p}{4}$$

This distance may be computed, like the distance D . Correction for a small error in the value of D' may be made by adjustment of the voltage at electrodes 22 and 24 by means of the voltage divider 40, to change the space charge wavelength λ'_p and make the current density maximum occur at the plane of the electrode 24.

In crossing the gap 25 between electrodes 24 and 26, the beam is accelerated abruptly to a relatively high D.-C. velocity which, in the present example, is the same as the original velocity u . This starts a further set of space charge waves having the same wavelength λ_p as the original set. Owing to continuity of current across the gap, the A.-C. current density on both sides is q_e . Since the

A.-C. velocity on the entrance side is zero, it is also zero on the exit side. Accordingly, the new waves start at the point c with A.-C. current density maximum, A.-C. velocity zero.

On leaving the gap between electrodes 24 and 26, the beam has the same D.-C. velocity and D.-C. charge density as it had when it left the helix 11, as well as the same kind of modulation. However, the A.-C. current density is much greater than it would have been if the beam had simply travelled at its original D.-C. velocity, and the beam is carrying space charge waves like those originally started on it by the input signal, but of larger amplitude, corresponding to $q_{max} = q_e$.

After the last acceleration at c , the beam goes through the output helix 27, including a wave thereon which gets its energy from the beam modulation and travels to the element 29 and into the output guide 35. Finally the beam strikes the collector electrode 3.

The total gain provided by the amplifier depends upon the structural design and the ratio between D.-C. velocities u and u' . The helices 11 and 27 may also contribute some gain, or loss, depending upon their lengths. Although the device of Fig. 1 has only one stage comprising a single deceleration followed by re-acceleration, any number of such stages may be similarly cascaded along a single beam, each additional stage providing additional gain, up to the point where the modulation of the beam, with a given input signal, becomes so great that small signal conditions no longer obtain. The structure of Fig. 1, when operated with 1900 volts on electrodes 17, 18 and 26, and 65 volts on electrodes 22 and 24, provides a gain of about 24 db at a frequency of 3000 megacycles per second, with a beam current of 0.6 milliampere.

The two stage amplifier shown in Fig. 4 includes an electron gun 1, collector 3, and input and output helices 11 and 27, all substantially the same as the correspondingly designated elements in Fig. 1. A series of apertured electrodes 41, 43, 45, 47, 49, 51, 53 and 55 are disposed between the inner ends of the helices 11 and 27 to define short axial gaps 42, 46, 50 and 54. The electrodes may be supported as shown by tubular members 58, 44, 48, 50 and 56 engaging the inner surface of the envelope 39. In a model of the device of Fig. 4 which has been constructed, the distance D'' between the gaps 42 and 46 is 0.86 centimeter. The distance D''' between the gaps 46 and 50 is 5.10 cm. The distance D'''' between gaps 50 and 54 is the same as D'' , 0.86 cm.

An external D.-C. source 37' is connected as shown to maintain the accelerator 9, collector 3, helices 11 and 27 and electrodes 58 and 56 at a high positive potential, for example 680 volts, with respect to the cathode 5. The electrodes 43 and 45 are supplied with a relatively low voltage, for example 66 volts. Electrodes 47 and 49 are held at a high potential, such as 500 volts. Electrodes 51 and 55 are at a low potential, for example 50 volts.

In the operation of the device, the electron beam is modulated by interaction with the input wave on the helix 11, then abruptly decelerated at the gap 42, which is in this instance located approximately at a velocity maximum, like the gap 21 in Fig. 1. A current maximum occurs at the gap 46, and here the beam is abruptly accelerated. A quarter space charge wavelength further on, at the gap 50, there is another velocity maximum, and the beam is again decelerated abruptly. At the gap 54 there is another current maximum, and the beam is accelerated again here to its original velocity, corresponding to 680 volts in the present example.

The A.-C. velocity is increased upon each deceleration, as described in connection with Fig. 1, and the original D.-C. velocity is partly or wholly restored to its original value upon each acceleration. When it leaves the gap 54 and enters the output helix, the beam is modulated in the same manner as it was when it left the input helix, but to a much greater extent. The amplified signal is

delivered by way of the helix 27 to the output guide 35 as in the system of Fig. 1.

With typical operating voltages as given above, the tube of Fig. 4 provides a total gain of 29 db at a frequency of 2891 megacycles per second, with a beam current of 0.5 milliampere. 9 db of this gain is contributed by the helices, acting as in a travelling wave amplifier, and 20 db is provided by the two space charge wave amplifier sections.

In the present stage of the art, the bandwidth of the amplifier is limited principally by that of the terminations, i. e. the coupling means between the helices and the wave guides. It will be apparent that any known broadband terminations may be used instead of those shown here by way of illustration.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A space charge wave amplifier including an electron gun adapted to direct a focussed beam of electrons along a substantially linear path, a conductive helix coaxially surrounding a part of said path adjacent said electron gun, and means for supplying high frequency electromagnetic wave energy which is to be amplified to said helix to modulate said beam and produce longitudinal plasma oscillation of the electrons therein; a pair of apertured electrodes surrounding said path and defining a decelerating gap at a point where the alternating current density amplitude of said beam is substantially zero, said gap being very short compared to the wavelength of said oscillation on said beam, another pair of apertured electrodes surrounding said path and defining an accelerating gap at a subsequent point on said path where the alternating velocity amplitude of said beam is substantially zero, said subsequent point being spaced from said first mentioned point by a distance that is substantially an odd integral multiple of one quarter of the wavelength of the plasma oscillation on said beam in the space between said gaps, said second gap being very short compared to said wavelength, a second conductive helix surrounding a part of said path beyond said electrodes, and means for taking amplified wave energy off said helix.

2. A space charge wave amplifier including an input helix and an output helix, said helices being coaxial and longitudinally spaced apart on their common axis, means for producing and directing a beam of electrons along said axis through said input and output helices in succession, means for applying an input signal to be amplified to said input helix to modulate said electron beam and produce space charge oscillations therein, and electrode means in the space between said helices defining a deceleration gap followed by an acceleration gap, said deceleration and acceleration gaps being very short compared to the distance between them.

3. A space charge wave amplifier including means for producing an electron beam, means responsive to high frequency electromagnetic wave energy input to modulate said beam and produce correlated space charge waves of alternating velocity and alternating current density thereon, the amplitudes of said waves varying periodically with longitudinal position on the beam, means for abruptly decelerating said beam at a point on its path where the alternating current density is approximately zero, to convert said space charge waves to a second set of waves having higher maximum amplitudes associated with a lower D.-C. velocity, means for abruptly accelerating said beam at a subsequent point on its path where the alternating velocity is substantially zero, to convert said second set of waves to a further set having substan-

tially the same maximum amplitudes as said second set and approximately the same D.-C. velocity as said first set, and means coupled to said beam beyond said subsequent point and responsive to said further set of space charge waves to produce an amplitude version of said input wave energy.

4. A space charge wave amplifier including means adapted to direct a focussed beam of electrons along an axis, means for modulating the beam with input signals to be amplified for providing correlated space charge waves of alternating velocity and alternating current density on said beam, a plurality of electrodes at spaced points along said axis and defining alternate decelerating gaps and accelerating gaps, said gaps being very short relative to their spacings from each other so that the electrons cannot appreciably change their relative spacings during transit of the gaps, and separated from each other by distances substantially equal to odd integral multiples of one quarter the space charge wavelengths in the spaces between the respective gaps, and means adjacent the path of said beam beyond said electrodes responsive to modulation of the beam after its passage through said series of gaps to produce an amplified version of said input signals.

5. A space charge wave amplifier including means for producing a modulated electron beam carrying correlated waves of current density and velocity variation, and a series of apertured electrodes at spaced points along the path of the beam defining at least one deceleration gap followed by at least one acceleration gap, both of said gaps being short relative to the space-charge wavelength so that the electrons cannot appreciably change their relative spacings during transit of the gaps with the deceleration gap being in the vicinity of a velocity maximum of said waves and the acceleration gap being in the vicinity of a velocity minimum of said waves, and separated from each other by a distance substantially equal to one quarter the space charge wavelength on the part of the beam between said gaps.

6. A space charge wave amplifier including means for producing a beam of electrons and directing said beam along a substantially lineal path with an initial D. C. velocity u , and D. C. charge density ρ , means for modulating said beam with an input signal to produce correlated waves thereon of A. C. current density variation of amplitude q and A. C. velocity variation of amplitude v , said waves having a length λ_p determined by said D. C. velocity u and D. C. charge density ρ ; means for abruptly decelerating said beam to a lower D. C. velocity u' , at a point where said A. C. current density q is substantially zero, to convert said waves to different waves having A. C. current density amplitude q' and A. C. velocity amplitude v' , with a length λ'_p which is shorter than λ_p ; means for abruptly accelerating said beam at a second point

λ'_p

4

distant from said first point, to a higher D. C. velocity approximately the same as said initial D. C. velocity u , and means surrounding a portion of said path subsequent to said accelerating means and responsive to the modulation on said beam to reproduce said input signal.

7. A space charge wave amplifier, including means for producing a modulated electron beam carrying correlated waves of alternating charge density and alternating velocity having a predetermined space charge wavelength, first means located at a first region along said beam in the vicinity of a space charge wave alternating charge density minimum for decreasing the wavelength and increasing the amplitudes of said space charge waves, and second means located at a second region along said beam in the vicinity of a space charge wave alternating charge density maximum for decreasing the wavelength and increasing the amplitudes of said space charge waves, each of said

first and second means being adapted to modify predetermined characteristics of said beam along a region substantially shorter than one-quarter of the space charge wavelength.
